DISPENSING PUMP ATTACHABLE TO THE NECK OF A CONTAINER FOR VISCOUS MATERIAL, HAVING AN INLET CONDUIT EXTENDING INTO SAID CONTAINER

"D" Flavius Bacheller, Glendale, Calif., assignor to "Pump-It" Incorporated, a corporation of California

Application June 12, 1947, Serial No. 754,091

3 Claims. (Cl. 222—385)

1

This invention relates to dispensers and more especially to a dispenser for a viscous material such as catsup or other food products contained in a bottle and covers improvements on my pending application, Serial No. 643,910, filed January 28, 1946, now Patent No. 2,521,961, dated Sept. 12, 1950.

An object of the invention is to provide a simple, practical and inexpensive dispenser of the character described.

Another object of the invention is to provide novel improvements in a plunger type dispenser for use with a bottled material of relatively viscous consistency, such as catsup or the like.

Another object of the invention is to provide an improved means for effecting the engagement of the dispenser with the neck of an associated bottle.

A further object of the invention is to provide improved plunger actuating means including a novel plunger seal.

Other objects and advantages will appear and be brought out more fully in the following specification considered with reference to the accompanying drawing, throughout which like parts are designated by like numerals.

Figure 1 is an elevation view, partly in section, showing my invention in association with a catsup bottle.

Figure 2 is an elevation view, partly in section, showing a dispenser and bottle neck engaging means.

Figure 3 is a sectional view taken along the line 3—3 of Figure 1.

Referring more particularly to the drawing, I show a catsup dispenser in association with a catsup bottle 10, the bottle having a reduced neck 12 and an upper annular rim 14 at the end of a throat 16 of the neck.

My novel catsup dispenser comprises a tubular member or cylinder 18, the upper end of which is secured to a collar element 20 which is formed with an annular recess 21 to receive the end of tubular member 18. A resilient sleeve 22, of rubber or similar material, is adapted to fit on neck 12 and has an internal annular groove 23 which interfits with a flange 24 on collar 20, thereby effecting a resilient seating engagement for the collar on the neck of a bottle, the engagement, however, being detachable, as should be obvious. Sleeve 22 has an annular groove 25 which interfits with an enlargement 26 of neck 12 and more effectively provides the attachment to the neck. Sleeve 22 thus effectively centers collar 20 with respect to the neck of the bottle.

2

A retainer 27, preferably of pressed sheet metal or a plastic of suitable strength, is provided for sleeve 22 which is positioned therein, the retainer having an upper end 28 which extends partially over collar 20, an aperture 29 being provided to permit plunger 52 to extend therethrough.

Tubular member 18 is formed with a restricted lower end portion 30 having a cylindrical extension 31 into which a draft tube 32 is inserted, tube 10. 32 having a lower end portion bent as shown and providing an inlet to the dispenser near the bottom of the bottle 10. End portion 30 is provided with a valve seat or port 36 forming an annular shoulder 38 which is formed with a plurality of recesses 40 for the seating of feet 42 of a web element 44. Element 44 has a vertical bore 46 forming a guide for the stem portion 48 of a check valve 50 which normally rests on valve seat 36 and closes the port opening thereof.

A tubular plunger 52 is reciprocably disposed in tubular member 18 and is operatively connected with a piston 53 by an integral or detachable interconnection, plunger 52 extending through an aperture 54 in collar 20 and having a reduced diametral portion 55 for effecting engagement with piston 53 and having an enlarged portion 56 adapted to effect an abutment engagement with an annular shoulder 58 on collar 20. A groove 57 is formed between piston 53 and enlargement 56 and a sealing ring 59 of any suitable sealing material is positioned in groove 57 to effect a fluid seal between plunger 52 and tubular member 18. Plunger 52 has a bore 60 and piston 53 has an enlarged bore 61, a shoulder 62 being formed at the upper end of bore 60. A coil spring 63 extends into bore 61 and engages web 44 to retain the web in engagement with reduced portion 30 of the tubular member.

The upper end of bore 60 provides a valve seat 40 for a dispensing valve 66 which is formed with a plurality of flutes 68 to permit the passage of the catsup or other dispensed material thereby. A cap member 70 is provided for the upper end of plunger 52 and has a stop shoulder 72 for valve 66 and a dispensing neck 76 extends from cap member 70 as shown.

Tubular member 18 is provided with a port or slot 80 at its upper end adjacent neck 12 of the bottle to act as a bleeder to admit air into tubular member 18 during the pumping action of plunger 52, thus preventing the discharge of dispensed material between enlargement 56 of the plunger and the wall portion of the tubular member 18.

The operation of the invention should be ap-

parent from the foregoing description. Upon reciprocation of plunger 52, a partial vacuum will be created in cylinder 18 and the bottled material, such as catsup or the like, will be drawn upwardly through tube 32 into the cylinder and out through the piston and dispensing neck 76. During the dispensing action, the upward movement of piston 52, which results in a dropping of valve 66, causes a slight return movement of the dispensed material in neck 76, and there are no surplus drops of the material, which would otherwise drop off or flow backwardly along the dispensing neck.

Collar 20, sleeve 22 and retainer 27 provide an effective seal between the collar and the neck of the bottle and no loss or seepage of the dispensed material can occur at the neck of the bottle. Furthermore, the seal, provided by ring 59, effectively prevents escape of the dispensed material past and externally of piston member 53 and through aperture 54, which might otherwise occur if such a seal is not provided.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices and systems.

Having thus described my invention, what I claim and desire to secure by Letters Patent is:

1. In a pump assembly adapted for insertion into bottles through the neck thereof the combination of a retaining and sealing device adapted to cooperate with the neck of a bottle comprising a collar having a diameter greater than the inside diameter of the neck and secured to said assembly, said collar having a shoulder adapted to overlie the rim of the neck, a sleeve of resilient material having an end portion surrounding and engaging the collar and a free portion smaller in inside diameter than the outside diameter of the neck, and a hollow cup-like retainer having a centrally perforated end in engagement with the collar and having a skirt, a portion of the skirt adjacent the perforated end forming in conjunction with the collar a confining space for reception of the end portion of the sleeve and adapted thereby to hold said sleeve in position on the collar.

2. In a pump assembly adapted for insertion into bottles through the neck thereof the combination of a retaining and sealing device adapted to cooperate with the neck of a bottle comprising a collar member having a diameter greater than the inside diameter of the neck and secured to said assembly, said collar member having a shoulder adapted to overlie the rim of the neck, a hollow cup-like retainer member having a centrally perforated end in engagement with

the collar member, portions of said retainer member and collar member adjacent said perforated end forming an annular space therebetween, an annular configuration on the portion of one of said members in the area of said annular space of diameter different from the diameter of said portion of the member bearing said configuration, a sleeve of resilient material having an end portion surrounding and engaging the collar member and engaging said configuration and a free portion adapted to engage the neck, said hollow cup-like retainer member having a skirt, a portion of the skirt adjacent the perforated end forming in conjunction with the collar member a confining space wherein the end portion of the sleeve is positioned, said retainer member and collar member being adapted thereby to hold said sleeve in position on the collar member.

3. In an elongated pump assembly adapted for insertion into bottles through the necks thereof the combination of a retaining and sealing device adapted to cooperate with the neck of a bottle for holding the assembly in place comprising a collar member having an outside diameter greater than the outside diameter of the pump assembly at the widest part thereof and secured to said assembly, said collar member having a shoulder adapted to overlie the rim of the neck, a sleeve of resilient material having a thickened portion surrounding and engaging the collar member and a free portion of reduced wall thickness larger in inside diameter than the outside diameter of the collar member, a hollow rigid cup-like retainer member having a centrally perforated end in engagement with the collar member and a skirt portion, the skirt portion adjacent the perforated end forming in conjunction with the collar member a confining space wherein the thickened portion of the sleeve is positioned, a flange on one of said members in engagement with the thickened portion of the sleeve whereby said sleeve is held in position with respect to the collar member, the remaining skirt portion of the retainer member having an inside diameter greater than the outside diameter of the free portion of the sleeve.
